(57) **CLAIM**

I claim the ornamental design for a thread guide for an embroidery sewing machine, as shown and described.

DESCRIPTION

FIG. 1 is a perspective view of a thread guide, for an embroidery sewing machine shown;

FIG. 2 is a front elevational view thereof;

FIG. 3 is a rear elevational view thereof;

FIG. 4 is a top plan view thereof;

FIG. 5 is a right-side elevational view thereof; and,

FIG. 6 is a left-side elevational view thereof.

The broken lines showing the unclaimed portions of the embroidery sewing machine, (e.g., four generally elliptical thread-passing holes (illustrated in FIGS. 1, 2, 4, 5, and 6) on each of the left and right sides of the thread guide, and two generally circular mounting screw holes (illustrated in FIGS. 1, 2, and 4) located substantially centrally relative to the left and right sides of the thread guide), are for illustrative purposes and form no part of the claimed design.
